Primary Examiner—Nelson C. Holtje**Attorney, Agent, or Firm—Wolf, Greenfield & Sacks****[57] CLAIM**

The ornamental design for a watch face, as shown and described.

DESCRIPTION

FIG. 1 is a front elevational view of a watch face showing my new design; and,

FIG. 2 is a typical side elevational view thereof. The rear of the watch face is flat, plain, and unornamented.

Fig. 1

Fig. 2
